LOCKING DEVICE

Gregory Laput, Brooklyn, N. Y.

Application September 13, 1934, Serial No. 743,803

6 Claims. (Cl. 292—155)

This invention relates to locking devices for sliding closures and has particular reference to a locking device for sliding window sashes of the standard household type.

5 The invention broadly aims to provide a sash lock mounted upon the upper rail of the inner sash adjacent one side thereof and which lock is so constructed and arranged as to exert a thrust or force diagonally of the two sashes so as to cause the inner and outer sashes to bind in opposite vertical corners of the frame in order to positively preclude relative movement of the sashes when locked.

10 The invention further resides in a lock which includes a slide member diagonally movable with reference to the inner sash and which is so contoured as to engage the adjacent faces of the inner vertical corners of the outer sash.

15 The invention more particularly includes a base member adapted to be fixedly mounted on the upper rail of the inner sash, a slide member carried by the base member for guided sliding movement diagonally of the sash rail, and a screw threadedly engaging the base member and swivelly connected with the slide member which is so constructed and arranged as to permit of the convenient assemblage of the device.

20 With these and other objects in view, reference is now made to the following specification and accompanying drawing in which there is illustrated a preferred embodiment of the invention, while the appended claims cover variations and modifications thereof which fall within their scope.

25 In the drawing:

Fig. 1 is a transverse sectional view taken approximately on the line 1—1 of Fig. 2.

30 Fig. 2 is a fragmentary vertical view of an inner and outer window sash and window frame with the locking device associated therewith.

35 Fig. 3 is a bottom face view of the locking device.

Fig. 4 is a side view of the locking device.

Fig. 5 is an end view of the locking device.

40 Fig. 6 is a top plan view illustrating the direction of the thrust exerted by the locking device and the position of the inner and outer sashes binding in opposite vertical corners of the window frame.

45 Referring to the drawing by characters of reference, A designates the inner and B the outer of a pair of sliding window sashes and C the window frame.

50 The locking device constituting the present invention and adapted for use in connection

5 with this type of window sashes, includes a base member 10 which is fixedly mounted upon the upper rail of the inner window sash A adjacent one side thereof and which carries a slide member 11 having an angulated head 12, which head is contoured to engage the adjacent faces of the inner vertical corner of the outer sash B.

10 The base member 10 includes a substantially L-shaped body having a vertically disposed guide wing 13 extending diagonally across the upper sash rail, and a vertically arranged bearing wing 14 extending in the plane of the sash and having a depending attaching flange 15 which overlies the front face of the upper sash rail and is provided with an opening 16 therethrough for receiving a screw or other means for affixing the same to the inner sash A. The guide wing 13 is also provided at its lower edge with an integral horizontally disposed flange 17 having a pair of screw openings 18 for receiving screws or other means for attaching the base 10 in superimposed position upon the upper sash rail.

15 The guide wing 13 is of cross sectional channel-shaped configuration having a depending spaced guide flange 19 along its upper edge and which forms therewith a longitudinally extending channel 20 opening through the inner end thereof. The angulated head 12 of the slide member 11 is also provided with a longitudinally 20 extending channel 22 in the upper face thereof and with a vertically disposed rearwardly extending guide flange 23, the upper portion of which is formed as a continuation of the flange 24 formed by the channel 22. The flange 24 25 and the channel 22 of the slide member 11, slidably interfits with the channel 20 and the flange 19 respectively of the guide wing 13 for guiding the sliding member diagonally of the sashes and for causing the angulated head 12 30 to exert a thrust against the adjacent faces of the inner corner of the outer sash B in the direction of the arrow 25 so as to cause the inner and outer sashes to bind in the opposite vertical corners D and E respectively of the window 35 frame C, while an inward thrust is exerted on the inner sash to cause its inner face to bind against the face F of the frame C.

40 The head 12 of the slide member 11 is provided with a keyhole slot 26 extending inwardly from the bottom face thereof and in which is swivelly received the enlarged head 27 of a screw 28, threadedly engaging the bearing wing 14 for effecting the sliding movement of the slide member with reference to the base mem- 45

50

55

ber 10 and for causing the head 12 of the sliding member 11 to be impinged against the inner vertical edge of the outer sash B, when the screw is rotated by means of its manipulating head 29. By providing the head of the slide member with the keyhole slot 26 which opens through and extends inwardly from the bottom face thereof, it will be apparent that the assembly of the screw 28 with the slide member may be inexpensively accomplished.

What is claimed is:

1. A lock for sliding window sashes including a base member adapted to be fixedly mounted upon the upper rail of the inner sash, a slide member carried by the base for guided sliding movement diagonally of said sash rail having a head conforming to and adapted to engage with the inner vertical corner of the outer sash for exerting a thrust diagonally of the two sashes to cause said sashes to bind in opposite vertical corners of the window frame.

2. A lock for sliding window sashes including a base member adapted to be fixedly mounted upon the upper rail of the inner sash, and comprising a cross sectionally channeled-shaped body disposed diagonally of said sash rail, a slide member having an angulated head conforming to and adapted to engage with the adjacent faces of the inner vertical corner of the outer sash, said slide member interfitting the channeled-shaped body of the base for guiding said slide member for sliding movement diagonally of the two sashes so as to exert a thrust diagonally thereof to cause the sashes to bind in opposite vertical corners of the window frame.

3. A lock for sliding window sashes including a base member adapted to be fixedly mounted upon the upper rail of the inner sash, a slide member carried by the base for guided sliding movement diagonally of said sash rail, said slide member having an angulated head conforming to and adapted to engage with the adjacent

faces of the inner vertical corner of the outer sash for exerting a thrust diagonally of the two sashes to cause said sashes to bind in opposite vertical corners of the window frame.

4. A lock for sliding window sashes including a base member adapted to be fixedly mounted upon the upper rail of the inner sash, a slide member carried by the base for guided sliding movement diagonally of said sash rail and having a portion conforming to and adapted to engage with the inner vertical corner of the outer sash for exerting a thrust diagonally of the two sashes to cause said sashes to bind in opposite vertical corners of the window frame, and means for effecting movement of said slide member with reference to the base member.

5. A lock for sliding window sashes including a base member adapted to be fixedly mounted upon the upper rail of the inner sash and consisting of a substantially L-shaped body having a vertically disposed guide wing extending diagonally across said sash rail and a bearing wing disposed vertically and extending in the plane of the sash and having a depending attaching flange overlying the front face of said sash rail; a slide member interengaging guide means on said slide member and guide wing for guiding the slide member diagonally of the sash, and a screw threadedly engaging the bearing wing and swivelly connected with the slide member.

6. A lock for sliding window sashes including a base member adapted to be fixedly mounted upon the upper rail of the inner sash, a slide member carried by the base for guided sliding movement, said slide member having a V-shaped head provided with angularly related portions conforming to and adapted to engage with the adjacent faces of the inner vertical corner of the outer sash for exerting a thrust to cause said sashes to bind in the window frame.

GREGORY LAPUT.
